IMPROVED MEANS OF PROVIDING A LEAK FOR LIQUIDS

Application filed June 17, 1931, Serial No. 545,136, and in Great Britain July 7, 1930.

Our invention relates to improved means of providing a leak for liquids, and may be used in conjunction with the invention relating to oil fuel burners, described in the specification No. 427,848, being primarily designed for use in conjunction with the reservoir of heated oil which supplies the burner, and adapted to take the place of the leak device, comprising a diaphragm, which is specifically described in the above-named specification. At the same time it will be obvious from the description to follow that the improved device may be used with advantage in any liquid fuel burning installation, where it is desired to provide, for similar reasons, leakage of liquid from a reservoir in which the liquid is contained.

In the fuel oil burning arrangement described in the above-cited specification, where the oil is supplied to a heating reservoir and thence to the burner, and where, during the quiescent period, the reservoir, the burner and their connecting conduits are filled with oil being heated and in thermosiphonic circulation, it is important to provide means for allowing a little oil to escape in order to relieve the system of such excess pressure as would cause ejection of oil through the burner nozzle during the quiescent period, and it is also desirable, during the active period, to provide a constant leak to carry away water and sediment which would otherwise accumulate at the bottom of the reservoir.

The improved leak device according to the present invention comprises a spring-loaded valve and a restricted leak orifice in series. The spring-loaded valve is preferably located between the leak orifice and the inlet to the device.

According to another feature of the invention, the leak device incorporates in its structure a filter or strainer for the leaking liquid.

In the preferred form, the leak device comprises a member containing a hand-operated valve and adapted to be connected to a liquid container to expose one side of the valve to the liquid, a filter chamber communicating with the other side of the valve, a spring-loaded check valve, preferably a ball valve, controlling the outlet from the filter cham-

ber to the space behind the check valve, a plug with a leak orifice providing a restricted outlet from the space behind the check valve, and a connector, preferably containing a valve, for coupling the final outlet from the leak device to a drain or to a return pipe leading to the main liquid supply or tank.

Our invention is illustrated by the accompanying drawing, in which Figure 1 is a longitudinal sectional elevation, and Figure 2 is a modified detail in longitudinal section.

Referring to the drawing:—

N is a nipple by means of which an angle pattern needle point valve A is attached to the underside of the heater vessel, i. e. the reservoir 9 of the arrangement described in specification No. 427,848. The valve A has its normal outlet at Q, but the underside of the valve body is drilled and fitted with a nipple R, upon which is mounted the sediment pocket B, by means of union nut S. The wheel of the valve fits on the valve spindle T. Screwed into the valve outlet Q is a filter housing C, into which housing is screwed the ball check valve body and filter stem E as one unit. The filter stem is wrapped with a single thickness of fine gauze or other straining medium D, and the liquid passing from the vessel through valve A into the filter body, can only find further egress by passing through the straining medium, through the holes Z in the filter stem to the ball check valve F, which seats at V. The ball check valve is loaded with a spring G which can be adjusted to give a varying pressure on the ball by means of the leak plug H, which is provided with a small orifice at W, which orifice limits the quantity of oil which passes out from the heater vessel. Secured to the end of the check valve body by means of union nut J and nipple K, is a small angle needle valve L, whose outlet M is coupled by a pipe to a main tank or to a drain.

The needle valve L serves as a complete shut off, or as a supplementary control agent to the leak orifice plug H in gauging the quantity allowed to flow from the vessel. By closing valve A, the entire leak assembly can be detached at O for examination and clean-

ing. Removal of sediment pocket B for cleaning is accompanied by a small beneficial flush of liquid from the vessel, which serves to clean out the valve body.

5. If it be desired to remove the filter or check valve or adjust the spring pressure on the check valve ball, valves A and L are both closed. Valve L is then disconnected from the check valve body at union J, and 10 the orifice plug H can be screwed in or out as desired, or the entire assembly can be unscrewed at joint O.

In normal operation valves A and L are fully open. When the vessel is full of liquid 15 being heated, and the plant is idle, the liquid expands, and under the resulting pressure the liquid finds egress via the leak orifice plug H, after being strained at D. When the plant is working, the normal working pressure in the 20 vessel causes a continuous small flow of liquid out of the vessel through the assembly and back to the tank via the pipe connected at M.

The assembly thus serves to drain away 25 continuously water and sediment which would otherwise accumulate at the bottom of the vessel. Further, it serves to relieve the vessel of a little liquid when the plant is idle and the liquid is expanding as a result of 30 being heated. Relief is afforded at the comparatively low pressures at which the ball check valve is set, and in this way liquid is prevented from being ejected from the nozzle assembly as a result of the high pressures 35 which would be reached were no such relieving device fitted.

Figure 2 shows a modified design of the filter, whereby a much greater surface of 40 straining medium is afforded. The ball, spring and leak orifice plug are the same as before, but the filter stem and check valve body are separate parts. The straining medium may conveniently consist of an open-ended cylinder D of gauze which is wired on 45 the bobbin rims at X and Y, and supported along its length internally by a helical spring P. The modified filter stem will be seen to consist of a bobbin-like part, one end of 50 which forms the ball valve seat, whilst the other end is provided with a head or driver slot I for ease in assembly. The neck of the bobbin is hollow for the greater part of its 55 length, with duct holes ZZ for the passage of the strained liquid.

What we claim is:

1. In combination with the heatable liquid-containing reservoir of a liquid fuel burning installation, a conduit connected to the bottom of said reservoir, a spring-loaded valve in said conduit, and a restricted leak orifice mounted in series with the spring-loaded valve, said valve being adjusted to open under the normal pressure within the 60 reservoir, when the installation is working,

to pass liquid from the reservoir through the leak orifice.

2. An arrangement as claimed in claim 1, in which a filter is disposed in the said conduit between the leak orifice and the reservoir. 70

3. In combination with the heatable liquid-containing reservoir of a liquid fuel burning installation, a conduit connected to the bottom of said reservoir, a spring-loaded ball check valve disposed in said conduit, and a plug within said conduit having a restricted leak orifice, said plug bearing on the spring of said spring-loaded valve and being adjustable in position so as to vary the compression of the spring, the said valve passing liquid from 80 the reservoir through the leak orifice. 85

4. In combination with the heatable liquid-containing reservoir of a liquid fuel burning installation, a conduit connected to the bottom of said reservoir, said conduit comprising 90 a filter casing, in which casing a hollow apertured stem projects, surrounded by straining material supported away from the stem by spacing means, one end of the internal cavity of said stem being open and forming a seat for a ball valve, a valve casing in said conduit, within which casing are arranged the said ball valve, a spring acting on said valve, and a plug with a restricted leak orifice bearing on 95 said spring and being in screw-threaded engagement with the inner wall of the valve casing, the said conduit passing liquid from said reservoir through said leak orifice. 100

5. An arrangement as claimed in claim 4 in which the conduit comprises an angle pattern needle point valve, connected at its upper side to the reservoir, and having a lateral passage adapted to be closed by the needle point and connected to said filter casing, and having a detachable sediment pocket connect- 105 ed to the underside.

6. An arrangement as claimed in claim 4 in which the filter stem is flanged at the ends within the filter casing so that it has the form of a bobbin by which the straining material is supported. 110

In testimony whereof we hereunto affix our signatures.

ISAAC LUBBOCK.
